UNITED STATES PATENT OFFICE.

RAFAEL RODRIGUEZ, OF DES MOINES, IOWA.

TROLLEY-SWITCHING MECHANISM.

Application filed February 14, 1925. Serial No. 9,112.

An object of this invention is to provide means for switching a trolley or current collector.

A further object of this invention is to provide a switch in an overhead conductor adapted to be operated coincident with a track switch, whereby a trolley or current collector may be passed automatically from a main line to a siding or branch without independent manipulation thereof.

A further object of this invention is to provide a switch in an overhead conductor whereby a trolley or current collector may be passed automatically from a main line to a siding or branch, or vice versa without independent manipulation of the trolley, and an attachment for a switch stand adapted to adjust said switch relative to said main line and operable coincident with a track switch controlled by said switch stand.

My invention consists in the construction, arrangement and combination of elements hereinafter set forth, pointed out in my claims and illustrated by the accompanying drawing, in which—

Figure 1 is a plan of my improved device as mounted for practical use, the main line being shown in the clear. Figure 2 is a side elevation of the same taken from a point across the track from the switch stand. Figure 3 is a horizontal section on an enlarged scale above the operating parts of the trolley-switching mechanism, a part being broken away to reveal construction. Figure 4 is a vertical section, on an enlarged scale, on the indicated line 4—4 of Figure 1, dotted lines indicating a different position of certain parts. Figure 5 is an enlarged side elevation showing the trolley switch in operative position relative to the main line overhead conductor. Figure 6 is an enlarged detail vertical section on the indicated line 6—6 of Figure 4, showing adjusting means.

In treating of the structure hereinafter set forth, it is assumed that the several overhead conductors are suitably supplied with electric current adapted to drive the motors of a trolley car located on the track or siding.

The numeral 10 designates generally a tower or frame adapted to be mounted around and rise from a switch stand 11, the latter containing operating mechanism, including a stem 12 and hand lever 13, adapted to move the points 14, 15 of a railway switch

whereby a railway car may be transferred from one to the other of main line track 16 and siding 17. A main line overhead electrical conductor 18 is shown supported in a common manner above and centrally of the main line track 16. A branch line overhead electrical conductor 19 is shown supported in a common manner, except as to an end thereof, above and centrally of the siding track 17. A standard 20 is fixed to and

rises from the stem 12 and is journaled for oscillation in the tower or frame 10 and is adapted to be turned on a vertical axis by and with the stem when the latter is operated in a common manner by the lever 13 to move the switch points 14, 15. Flags 21, 22, preferably white and red respectively to correspond with lenses in a bull's-eye lamp 23 carried by the stand 11, are mounted at right angles to each other on the upper end of

the standard 20 and, like the lamp, indicate the relative positions of the points in respect of the main line or siding. A plurality of rods, 24, 25 and 26, are slidably mounted side by side in the same horizontal plane in the upper portion of the tower and said rods are connected rigidly by a spider 27 located within and spaced from the side walls of the tower. The end portions of the rods adjacent the tracks are bent upwardly and carry horizontal spaced arms 28, 29 and 30 integral therewith, which arms are adapted to extend partially transversely of the switch points 14, 15 in a horizontal

plane above the main line conductor 18. A crank-arm 31 is fixed to and extends laterally from the standard 20 below the central rod 25, within the tower, and a link 32 is pivoted at its ends to and connects said arm and the central portion of said rod. Hence, when the standard 20 is oscillated, the crank-arm 31 and link 32 will reciprocate the spider and rods relative to the tower and move the arms and rods transversely of and relative to the tracks. The outer portions of the arms 28, 29 and 30 are angular in cross-section and angular collars 33, 34 and 35 are slidably mounted thereon and are adapted to be secured in desired ad-

justment longitudinally thereof by set screws 36. The collars 33, 34 and 35 are insulated from the arms 28, 29 and 30 by suitable members 37, 38 (Fig. 6) of fiber interposed between them and forming a slide bearing for each arm as well as a clamp for the set screws 36. Vertical openings are formed

in the collars 33, 34 and 35 adjacent the arms and hangers 37, 38 and 39 are slidably mounted vertically therein and secured by set screws 40 thereto. A switch point 41, preferably made of metal of good electrical conductivity such as copper, is fixed to and connects the lower ends of the hangers 37, 38 and 39 and is adapted to be supported by said hangers in a horizontal plane slightly lower than that of the adjacent portion of the main line conductor 18. One end portion 42 of the switch point 41 is inclined and the opposite end portion thereof is secured, preferably rigidly, to the adjacent end of the siding conductor 19. An offset 43 is formed in each of the hangers 37, 38 and 39 above the switch point 41 and opposite thereto, to permit the point 41 to be located adjacent to and below (in the same vertical plane with) the adjacent portion of the main line conductor 18. When the main line is in the clear and it is desired to move a car upon the siding, the switch point 41 occupies the position shown in Figures 1 and 4 at one side of and below the main line conductor. When the lever mechanism is operated to throw the points 14, 15 to cause the car to take the siding, the switch point 41 is moved, by the connecting mechanism into the position shown by dotted lines in Figure 4, in order that the trolley wheel or current collector may travel from the conductor 18 beneath and in contact with said point 41. If the car is to be moved in the opposite direction, the trolley will move from the point 41 to the conductor 19.

I claim as my invention--

1. In an apparatus of the character described having a track switch, switch stand, operating mechanism therefor, main line 40 and siding conductors, a trolley-switching apparatus comprising a support, a standard mounted therein for oscillation on a vertical axis, operative connections between said standard and the operating mechanism of 45 the track switch, spaced rods slidably mounted in said frame and rigidly connected, operative connections between said standard and rods, arms on said rods adapted to extend at times over and across said 50 main line conductor, and a switch point carried by said arms and fixed to and forming a continuation of said siding conductor, said switch point being adjustable longitudinally and laterally of said arms and adapted to be 55 moved thereby laterally of and relative to and below said main line conductor, one end portion of said switch point being inclined upwardly toward the main line conductor, said arms being offset to arch around said 60 main line conductor at times.

2. In an apparatus of the character described, a frame formed of spaced rods mounted for reciprocation and a spider connecting said rods, end portions of said rods 65 being bent vertically, arms on said bent portions of the rods, collars slidably mounted on said arms and adapted to be fixed thereto, hangers slidably mounted in said collars and adapted to be fixed thereto, and a switch 70 point fixed to said hangers and adapted to be moved laterally thereby.

RAFAEL RODRIGUEZ.
